UNITED STATES PATENT OFFICE.

VILMA STANISITS, OF ROCKVILLE CENTER, NEW YORK.

DESIGN FOR A JAR OR SIMILAR RECEPTACLE.

Application filed June 27, 1922. Serial No. 2,835. Term of patent 3½ years.

To all whom it may concern:

Be it known that I, VILMA STANISITS, a citizen of the United States, residing at Rockville Center, L. I., in the county of Nassau and State of New York, have invented a new, original, and ornamental Design for a Jar or Similar Receptacle, of which the following is a specification, reference being had to the accompanying drawing, forming a part thereof.

The figure is a view of a jar or similar receptacle embodying my design.

I claim:

The ornamental design for a jar or similar receptacle as shown.

VILMA STANISITS.
